DESIGN FOR AN INHALER

Philip A. Derham and Jesse H. Newport, Jr., Rosemont, Pa., assignors to Victor Metal Products Corporation, Brooklyn, N. Y., a corporation of New York

Application February 26, 1942, Serial No. 105,988

Term of patent 7 years

To all whom it may concern:

Be it known that we, Philip A. Derham and Jesse H. Newport, Jr., citizens of the United States and residents of Rosemont, in the county of Montgomery and State of Pennsylvania, have invented a new, original, and ornamental Design for an Inhaler, of which the following is a specification, reference being had to the accompanying drawing, forming part thereof.

Fig. 1 is a perspective view of an inhaler showing our new design.

Fig. 2 is a top plan view of the same.

Fig. 3 is a front view of the same showing the cap portion separated from the remaining portion.

We claim:

The ornamental design for an inhaler, substantially as shown.

PHILIP A. DERHAM.
